TOY AIRPLANE

Allan J. Alvaney, Arlington Heights, Ill., assignor to
Sears, Roebuck and Co., Chicago, Ill., a corporation
of New York

Filed Dec. 1, 1960, Ser. No. 63,053

Term of patent 7 years

(Cl. D34—15)

FIG. 1 is a front perspective view of a toy airplane showing my new design, and

FIG. 2 is a rear perspective view of same.

The dominant features of my design reside in the portions shown in full lines.

I claim:

The ornamental design for a toy airplane, substantially as shown and described.
